DISPOSABLE STETHOSCOPE TRANSDUCER

Sydney Hudspith, San Diego, Calif., assignor to
Ivac Corporation, San Diego, Calif.

Filed Nov. 1, 1971, Ser. No. 194,775

Term of patent 14 years

Int. Cl. D24—02

U.S. Cl. D83—12

FIG. 1 is a front perspective view of a disposable stethoscope transducer showing my new design;

FIG. 2 is a front elevational view of the transducer shown in FIG. 1;

FIG. 3 is a rear elevational view of the transducer shown in FIG. 1;

FIG. 4 is a top plan view of the transducer shown in FIG. 1; and

FIG. 5 is a right side elevational view of the transducer shown in FIG. 1.

I claim:

The ornamental design for a disposable stethoscope transducer, as shown.
